REFRIGERATION SYSTEM

Marion R. Moore, Atlanta, Ga., assignor of one-third to C. L. Emerson, Fulton County, Ga., and one-third to Bryan M. Blackburn, Coweta County, Ga.

Application July 24, 1934, Serial No. 736,798

18 Claims. (Cl. 62—125)

This invention relates to a refrigeration system of that type in which the liquefaction of the volatile refrigerant is accomplished in the condenser without the aid of a compressor by a heat abstracting medium, such as ice, or the evaporating element of a mechanical refrigeration system.

It is essential to a system of the type described for means to be provided for conducting the liquefied refrigerant from the condenser back to the evaporator or at least as far as the expansion valve which admits the refrigerant to the evaporator. Otherwise the system becomes static since pressure developed in the evaporator by the volatilization of the refrigerant acts with substantially equal pressure at both ends of the evaporator coil.

One of the objects of the present invention is to provide a pump for the liquid refrigerant which operates responsive to pressure differential between the high and low sides of the refrigeration circuit.

Another object of the invention is the provision of a pump having pistons of different area whereby the pressure differential between the high and low sides of the system is magnified.

Since by virtue of its position between the high and low limbs of the refrigeration circuit the motor element of the pump must be actuated by a fluid which has already done the major portion of its expanding in the evaporator, provision is made for maintaining the motor cylinder in communication with the low side of the refrigeration system during substantially the entire working stroke of the piston whereby the latter is impelled throughout its stroke by pressure derived in the main from expansion outside the cylinder. Consequently, another object of the invention is the provision of valve control means for the motor cylinder of the pump designed to hold the inlet valve open and the exhaust valve shut during the working stroke of the motor cylinder and to snap the inlet valve suddenly into closed position, and the exhaust valve into open position, when the piston approaches the lower limit of its range of travel, the operation being reversed when the piston reaches its upper limit.

A further object of the invention is the provision of a pump in which both the motor and pumping pistons are spring returned.

A further object of the invention is to provide means for cooling the pumping cylinder so that the liquefied refrigerant will not flash into a gas in the pumping cylinder upon the suction stroke of the pumping piston.

Other objects of the invention will appear as

the following description of a preferred and practical embodiment thereof proceeds.

In the drawings which accompany and form a part of the following specification and throughout the several figures of which the same characters of reference have been employed to designate identical parts:

Figure 1 is a vertical section through the pump taken somewhat irregularly along the line 1—1 of Figure 2;

Figure 2 is a horizontal section taken along the line 2—2 of Figure 1. The arrows along the section lines indicate the direction of aspect;

Figure 3 is a vertical elevation viewed from the right in Figure 1;

Figure 4 is a section through the piston taken along the line 4—4 of Figure 1;

Figure 5 is a side elevation of the snap action which controls the inlet valve in the opposite position to that shown in Figure 3;

Figure 6 is a detail in end elevation showing the cam which is fixed to the piston operated sleeve;

Figure 7 is an end view of the said sleeve with the inlet and exhaust cams secured thereto, showing their relative positions;

Figure 8 is a vertical section illustrating the refrigeration system;

Figure 9 is a section taken along the line 9—9 of Figure 2; and

Figure 10 is a detail view largely diagrammatic showing the pump unit and a portion of the condenser, indicating an arrangement of conduits adapted for thermosyphonic flow of the brine.

Referring now in detail to the several figures and first advertizing to the system shown in Figure 8, the numeral 1 represents the pump which is intercalated between the high side 2 and the low side 3. The pump is actuated by gaseous refrigerant under pressure passing from the evaporator 4 to the condenser 5. The pump inducts liquid refrigerant by way of the conduit 6 from the lower part of the condenser and forces it into a receiver 7 and into a conduit 8 up to the expansion valve 9 where the liquid refrigerant is admitted to the evaporator coil according to the refrigerating needs determined by a thermostat 10 in the refrigerated chamber 11 which thermostat controls the functioning of the expansion valve.

Turning now to Fig. 1, the pump 1 comprises a casing forming a cylinder 12 for the motor piston secured to a second casing forming a pumping cylinder 13, the pumping cylinder be-

ing co-axial with the motor cylinder. Within the respective cylinders are the motor piston 14 and pumping piston 15, said pistons being unitarily related, the pumping piston being screwed 5 into a socket in the underside of the motor piston, as shown.

A spring 16 surrounds the pump cylinder and has its upper end preferably seated in an inverted cup-like collar 17 suitably secured. The 10 spring 16 normally biases both pistons to the upper end of their stroke.

The motor cylinder as shown is of the T-head type being provided with intake and exhaust valve chambers 18 and 19, respectively, communication of the motor cylinder with said chambers being controlled by the respective inlet and exhaust valves 20 and 21. Said valves are operated by cams 22 and 23 fixed upon a shaft 24 best shown in Figure 2, in such relation that 20 when the inlet valve is open the exhaust valve is closed and vice versa. As will be shown, the said valves do not operate in complete synchronism with the motor piston 14 since it is essential that the motor piston shall have traversed 25 its stroke in one or the other directions before one valve opens and the other closes, and in the interest of efficiency, it is necessary that the inlet valve shall be fully open and the exhaust valve fully closed during the entire duration of the 30 working stroke of the motor piston.

Since the pressure of the gaseous refrigerant which operates the motor piston 14 is at the best slight, conservation means are employed to prevent leakage, said means including a sylphon 25 bridging the joint between the inlet valve stem 26 and the guide 27 within which it reciprocates. The upper end of said sylphon is welded to the valve stem at 28 while the lower end is expanded into a cup 29 which is pressed in fluid-tight manner into the bottom of a recess 30 formed at the upper end of the valve guide 27.

Such expedient is not necessary with regard to the exhaust valve 21 since the joint between the exhaust valve stem 31 and the guide 32 is outside of the cylinder chamber and not in a position where leakage of gas would be of any consequence.

The casting which forms the pump cylinder 13 is formed as a plate 33 constituting a head for 50 the lower end of the motor cylinder, said plate being secured in fluid-tight manner to the underside of the casting 12, a gasket 34 preferably of heat insulating material and it is also preferred to interpose heat-breaking strips 73 and 74 between those parts of the cylinder casting 13 which would otherwise come into contact with or in close proximity to the cylinder 1. Thus heat lost from the cylinder 1 to the cold cylinder 13 is minimized, 60 avoiding the probability of any refrigerant in the cylinder 1 condensing into a liquid.

The fluid-tight connection of the plate 33 with the casting which forms the cylinder 12 prevents any refrigerant in gaseous state which may 65 leak past the rings of the piston 14 into the chamber beneath the piston from escaping into the chamber 37 and going out with the brine which flows through said chamber. The wall of the cylinder 12 is perforated at 71 permitting 70 said gases as may get by the piston rings to enter the valve chamber and to pass through a port 72 into the exhaust valve chamber 19 to be carried away through the high side of the refrigeration system to the condenser.

75 The casting forming the cylinder 12 is sup-

ported upon a hollow base 35 closed at its bottom by a plate 36 and defining a chamber 37 into which the lower portion of the pump cylinder protrudes. Check valves 38 and 39 are in communication with the pump cylinder, one opening toward and the other away from said cylinder as shown, and constituting the eduction and induction valves for the pump cylinder 13. The valve 38 leads to the receiver 7 while the valve 39 communicates with the conduit 6 which comes from the lower part of the condenser. Cover plates 40 and 41 occlude openings in opposite sides of the cylinder casting and give access to the operating mechanism which actuates the inlet and exhaust valves 20 and 21.

Now referring to the means which retards the actuation of the valves until the motor piston has approached the end of its stroke in either direction, Fig. 2 indicates a sleeve 42 surrounding the shaft 24. Said sleeve oscillates synchronously with the reciprocation of the piston 14 by means of a crank 43 keyed to said sleeve and connected to the piston by a connecting rod 44, the latter having its upper end pivoted on a pin 45 mounted in the piston body at its lower end and pivoted to the crank 43. When the piston descends, the crank 43 rocks downwardly and when the piston 14 ascends the crank reverses the direction of its motion.

Fixed to the end of the sleeve 42 adjacent the inlet cam 22 is an oscillating actuator 46, see Fig. 6. Said actuator has the form of a crank, having an outwardly projecting lug 47. Said lug extends through an arcuate slot 48 formed in the inlet cam 22, the length of the slot being such that the lug does not directly disturb the repose of said cam in the course of oscillation of said actuator. The lug 47 extends through an arcuate slot 49 in a snap hammer 50 freely mounted upon the end of the shaft 24 and retained against endwise displacement by any suitable means such as the split ring 51 which seats in a groove in said shaft. The snap hammer is biased to one side or the other by a coil spring 52, the upper end of which is suitably anchored to a fixed part of the structure. In the oscillation of the snap hammer the spring is stretched as it crosses dead center and throws the hammer with considerable force to one or the other side of dead center according to the direction of movement of said snap hammer.

The concerted action of the parts is thus: Assuming the inlet cam 22 to be holding the inlet valve 20 open as in Figure 3, the piston starts to descend, oscillating the shaft 24 so as to bring the actuator downward. The lug 47 on the actuator comes into contact with the right hand end of the short slot 49 in the snap hammer. It pulls the snap hammer down until the pin 53 which anchors the spring 52 to the snap hammer is at dead center. During all this time the cam 22 has not been moved in view of the amplitude of the slot 48. The lug 47 draws the snap hammer 50 beyond dead center whereupon the spring 52 freely contracts throwing the snap hammer quickly upwardly bringing the shoulder 54 into impactive contact with the pin 55 on the inlet cam throwing said cam over to the position shown in Figure 5 in which the nose 56 of said cam is out of contact with the valve stem 26, permitting the valve to close. The exhaust cam 23 being fixed to the same shaft as the inlet cam 22 has oscillated through a similar arc and opened the exhaust valve. Instantly, the energy of the spring 75

16 overcomes the pressure of the gaseous refrigerant escaping through the exhaust valve and the motor piston rises to the top of its stroke. In doing this it oscillates the actuator in the opposite direction. The lug 47 which starts from the position shown in Figure 5 moving clockwise drawing the snap hammer downwardly in the opposite direction against the tension of the spring 52 until dead center has been passed whereupon the snap hammer over-runs the lug 47 which brings its shoulder 57 into impactive contact with the pin 58 on the opposite side of the inlet cam, throwing said cam back into the position in which the nose 56 engages the valve stem 15 holding the inlet valve open. By the same movement the exhaust valve is closed.

It is to be noted that the valves are arranged in such a manner that on the downward stroke the gas pressure exerts itself on top of the exhaust valve, helping to keep it seated. On the upward stroke the high pressure gas is exerted on top of the intake valve to aid in seating it. This lessens the duty required of the valve springs.

Since the pump piston is unitary with the motor piston it performs its cycle simultaneously. When it ascends, it draws liquid refrigerant through the check valve 39 from the condenser. When it descends the check valve 39 closes against back pressure of the refrigerant, and the check valve 38 opens, the liquefied refrigerant being forced outwardly through the check valve 38 and into the receiver.

As the liquefied refrigerant is near its critical state it is obvious that unless provision be made to prevent it, the liquid will flash into a gas within the pump cylinder 13 when the pumping piston rises. This is avoided by admitting cold brine to the chamber 37 which brine cools the liquid refrigerant down to such a temperature that it will not volatilize upon the reduction of pressure incident to the lifting of the pumping piston 15.

The brine is conducted from the lower part of the condenser tank 59 by a pipe 60 opening into the chamber 37 at 61. The chamber discharges through the port 62 by way of a pipe 63 shown in Fig. 8. The head of liquid brine in the condenser tank 59 is regulated by having the pipe 63 swivelled so that its discharge end 64 can be moved upwardly or downwardly as indicated by the dotted arc 65. The brine level is preferably kept at such point that the chamber 37 will always be substantially full.

The liquid refrigerant in the pump cylinder is also kept from any tendency to flash into a gas when the pressure is relieved on the suction stroke of the pump piston, by the relative level of the bottom of the condenser coil 5 to the upward limit of the stroke of the pump piston. The bottom limb of the coil 5 which may be considered at the same level as the liquefied refrigerant, is preferably several inches higher than the upper end of the pump cylinder when the pump piston is at the top of its stroke. This head of liquid exerts a pressure upon the liquid in the cylinder and raises the point at which it will vaporize.

Figure 10 shows an alternative arrangement for connecting the condenser to the brine space within the base, which is employed when the brine is not continuously replenished as in the case of ice, but recurrently circulated as when a mechanical refrigerating unit is employed to cool the condenser or when eutetic brine is employed. In order to produce a closed path for the ther-

mosiphonic circulation of brine, the inflow pipe 60 enters the base of the pump unit near the bottom, while the pipe 63 is no longer swivelled, but connected to the condenser chamber near the top.

The pump 1 is preferably seated in a pan 66 which collects melting frost that may from time to time run down from the surface of the pump. The pan drains by way of a pipe 67 and in order that the inlet of the pipe 67 shall not become frozen causing overflow of the pan 66, the brine from the pipe 63 preferably overflows into the said pan.

The condenser is preferably of the cross fin construction comprising horizontal ranks and 15 banks of tubes, the tubes in common passing through the plates or fins 68. The fins are extended downwardly to the bottom of the liquid brine so as to take full advantage of the cooling effect of the brine. The tank 59 as shown 20 is designed to be packed with a mixture of ice and salt.

The receiver 7 is formed with a pressure equalizing chamber in its upper end which may comprise a sylphon 69 kept open by an internal expanding spring 70. When a sudden increase in the refrigerating demands occurs and the receiver 7 tends to empty faster than it is supplied by the pump, the sylphon expands. When the opposite conditions prevail, that is to say, when the thermostat 10 first closes the expansion valve 9, and the pump supplies liquid to the receiver faster than it is fed to the expansion valve, the sylphon contracts. In the ordinary operation of the system however, the work done by the pump 35 is in direct proportion to the demands of the evaporator and consequently, the pressure in the receiver will be substantially uniform.

In view of the high efficiency in the functioning of this pumping unit due in the first place 40 to the admission of the actuating fluid during the entire working stroke, and also owing to the differential ratio in the areas of the motor and pumping pistons, an adequate working pressure is developed enabling the evaporator unit to be 45 located within any reasonable distance remote from the condenser and pumping mechanism. Thus it is quite feasible to have the condenser and pumping unit occupy the space now devoted to one of the ice bunkers at the ends of a 50 freight car. The other ice bunker may be done away with increasing the capacity of the car and the evaporator may be situated in any desirable location as for example, along the roof of the car without regard to the position of the 55 pump and condenser. This is only one of the exemplary utilizations of the present invention.

What I claim is:

1. Refrigeration system including an evaporator and a condenser with high and low side connections therebetween, a receiver in said low side connection, an expansion valve thermostatically responsive to refrigerating demands in said high side connection adjacent said evaporator, a pump for maintaining a head of liquid refrigerant in 65 said low side up to said expansion valve having a motor element actuated by gaseous pressure in the high side, said expansion valve normally controlling the actuation of said pump according to refrigerating demands, and compensating means 70 in said receiver for substantially equalizing the pressure of liquid in said receiver at the moment of opening and closing of said expansion valve.

2. Refrigeration system comprising a closed conduit including a circulation path for a re- 75

- frigerant passing through a cycle involving a change of state, a pump including a motor cylinder and pumping cylinder with synchronously moving pistons in said cylinders, the pumping 5 piston actuating fluid in the liquid limb of said circulation path, the motor piston being actuated by fluid pressure generated by the expansion of a gas in the gas limb of said circulation path, inlet and exhaust valve serving said motor cylinder, and operating mechanism for said valves determining a simultaneous lag in the closing of said inlet valve and the opening of said exhaust valve until the piston has reached the downward limit of its stroke, whereby the motor piston will 10 be exposed to the pressure in said gas limb during its entire working stroke.
3. Refrigeration system comprising a closed conduit including a circulation path for a refrigerant passing through a cycle involving a change of state, a pump including a motor cylinder and a pumping cylinder with unitarily related pistons operating therein, the pumping piston actuating fluid in the liquid limb of said circulation path, the motor piston being actuated by 15 fluid pressure generated by the expansion of a gas in the gas limb of said circulation path, inlet and exhaust valves serving said motor cylinder, and operating mechanism for said valves determining a simultaneous lag in the closing of said inlet valves and the opening of said exhaust valve until the piston has reached the downward limit of its stroke, whereby the piston will be exposed to the gas pressure during its entire working stroke, said valve operating mechanism comprising a shaft, an inlet and an exhaust cam on said shaft engageable with the stems of the corresponding valves, said cams being so displaced as to cause the simultaneous closing of one valve and the opening of the other, means oscillated by 20 said piston, normally moving independently of said shaft, but operably engaged therewith at the extremities of the piston stroke for oscillating said shaft.
4. Refrigeration system comprising a closed conduit including a circulation path for a refrigerant passing through a cycle involving a change of state, a pump including a motor cylinder and a pumping cylinder with unitarily related pistons operating therein, the pumping piston actuating fluid in the liquid limb of said circulation path, the motor piston being actuated by 25 fluid pressure generated by the expansion of a gas in the gas limb of said circulation path, inlet and exhaust valves serving said cylinder, and operating mechanism for said valves determining a simultaneous lag in the closing of said inlet valves and the opening of said exhaust valve until the piston has reached the downward limit of its stroke, whereby the piston will be exposed to the gas pressure during its entire working stroke, said valve operating mechanism comprising a shaft, an inlet and an exhaust cam on said shaft engageable with the stems of the corresponding valves, said cams being so displaced as to cause the simultaneous closing of one valve and the opening of the other, means oscillated by 30 said piston, normally moving independently of said shaft, but operably engaged therewith at the extremities of the piston stroke for oscillating said shaft.
5. Refrigeration system including an evaporator and a condenser with high and low side connections therebetween, an expansion valve in said high side connection adjacent said evaporator, a pump for maintaining a head of liquid refrigerant in said low side up to said expansion valve, said pump having a motor cylinder and pump cylinder with synchronously moving pistons therein, the motor cylinder being intercalated in the high side connection and the motor piston being actuated by gaseous pressure generated by expansion of the gaseous refrigerant, for the most part externally of said motor cylinder, inlet and exhaust valves serving said motor cylinder, and means delaying the closing of the inlet valve and opening of the exhaust valve until the piston has substantially reached the downward limit of its stroke, whereby the piston will be exposed to the extraneously generated pressure during its entire working stroke.
6. Refrigeration system as claimed in claim 5, said pistons being spring returned.
7. Refrigeration system including an evaporator and a condenser with high and low side connections therebetween, a receiver in said low side connection, an expansion valve in said high side connection adjacent said evaporator, thermostatically responsive to refrigerating demands, a pump for maintaining a head of liquid refrigerant in said low side up to the expansion valve, said pump having a motor cylinder and a pump cylinder, with synchronously moving pistons therebetween, the motor cylinder being intercalated in the high side connection and the motor piston being actuated by gaseous pressure generated by expansion of the gaseous refrigerant, for the most part externally of the motor cylinder, inlet and exhaust valve serving said motor cylinder, means delaying the closing of the inlet valve and the opening of the exhaust valve until the piston has substantially reached the downward limit of its stroke, whereby the piston will be exposed to the extraneously generated pressure during its entire working stroke, said expansion valve normally governing the actuation of said pump according to refrigerating demands through its control of the refrigerant admitted to said evaporator, and compensating means in said receiver for substantially equalizing the pressure of liquid in said receiver at the moment of opening and closing said expansion valve.
8. Refrigeration system including an evaporator and a condenser with high and low side connections therebetween, an expansion valve in said high side connection adjacent said evaporator, a pump for maintaining a head of liquid refrigerant in said low side up to said expansion valve, said pump having a motor cylinder and pump cylinder with synchronously moving pistons therein, said cylinders being intercalated respectively in said high and low side connections, the motor piston being actuated by gaseous pressure generated by expansion of the gaseous refrigerant, for the most part externally of said motor cylinder, inlet and exhaust valves serving said motor cylinder, means delaying the closing of the inlet valve and the opening of the exhaust valve until the piston has substantially reached the downward limit of its stroke whereby the motor piston will be exposed to the extraneously generated pressure during its entire working stroke, and means for preventing the liquid refrigerant in the pump cylinder flashing into a gas on the suction stroke of the pump piston.
9. Refrigeration system including an evapora-

- tor and a condenser with high and low side connections therebetween, an expansion valve in said high side connection adjacent said evaporator, a pump for maintaining a head of liquid refrigerant in said low side up to said expansion valve, said pump having a motor cylinder and pump cylinder with synchronously moving pistons therein, said cylinders being intercalated respectively in said high and low side connections, the motor piston being actuated by gaseous pressure generated by expansion of the gaseous refrigerant, for the most part externally of said motor cylinder, inlet and exhaust valves serving said motor cylinder, means delaying the closing of the inlet valve and the opening of the exhaust valve until the piston has substantially reached the downward limit of its stroke whereby the motor piston will be exposed to the extraneously generated pressure during its entire working stroke, and means for cooling said pump cylinder to prevent the liquid refrigerant in the pump cylinder flashing into a gas on the suction stroke of the pump piston.
10. Refrigeration system including an evaporator and a condenser with high and low side connections therebetween, an expansion valve in said high side connection adjacent said evaporator, a pump for maintaining a head of liquid refrigerant in said low side up to said expansion valve, said pump having a motor cylinder and pump cylinder with unitarily related pistons therein, said cylinders being intercalated respectively in said high and low side connection, the motor piston being actuated by gaseous pressure generated by expansion of the gaseous refrigerant, for the most part taking place externally of said motor cylinder, inlet and exhaust valves serving said motor cylinder, means for delaying the closing of said inlet valve and the opening of the exhaust valve until the piston has substantially reached the downward limit of its stroke whereby the piston will be exposed to the extraneously generated pressure during its entire working stroke, said condenser including a coil in a brine tank, means for maintaining a head of brine in said brine tank, means connecting said brine tank with the chamber of said base, said chamber having a brine discharge ensuring a flow of cooling brine about said pump cylinder to prevent the liquid refrigerant in the pump cylinder flashing into a gas on the suction stroke of the pump piston.
15. Refrigeration system as claimed in claim 12, the area of the motor piston being greater than that of the pump piston.
16. Refrigeration system including an evaporator and a condenser with high and low side connections therebetween, an expansion valve in said high side connection adjacent said evaporator, a pump for maintaining a head of liquid refrigerant in the low side up to said expansion valve, said pump bridging the high and low side connections between said evaporator and condenser, having motor and pump cylinders intercalated in said high and low side connections respectively with synchronously moving pistons therein, the motor piston being actuated by gaseous pressure generated by expansion of the gaseous refrigerant, said condenser including a coil in a brine tank, means for maintaining a head of brine in said brine tank, and means for conducting brine from said brine tank about said pump cylinder to prevent the liquid refrigerant in the pump cylinder flashing into a gas on the suction stroke of the pump piston.
17. Refrigeration system including an evaporator and a condenser with high and low side connections therebetween, an expansion valve in said high side connection adjacent said evaporator, a pump for maintaining a head of liquid refrigerant in the low side up to said expansion valve, said pump bridging the high and low side connections between said evaporator and condenser, having motor and pump cylinders intercalated in said high and low side connections respectively with synchronously moving pistons therein, the motor piston being actuated by gaseous pressure generated by expansion of the gaseous refrigerant, said condenser including a coil in a brine tank, means for maintaining a head of brine in said brine tank, means for conducting brine from

said brine tank about said pump cylinder to prevent the liquid refrigerant in the pump cylinder flashing into a gas on the suction stroke of the pump piston, and means for varying the head of brine in said brine tank.

- 5 16. Refrigeration system including an evaporator and a condenser with high and low side connections therebetween, an expansion valve in said high side connection adjacent said evaporator, 10 a pump for maintaining a head of liquid refrigerant in said low side connection up to said expansion valve, said pump bridging said connections having a motor cylinder intercalated in the high side connection and a pump cylinder in the low side, with synchronously moving pistons 15 therein, said motor piston being actuated by gaseous pressure generated by expansion of gaseous refrigerant mainly in said evaporator, said condenser including a coil in a brine tank, means 20 for maintaining a head of brine in said brine tank above the level of at least a portion of said pump cylinder, means for conducting brine from said brine tank about said pump cylinder to prevent the liquid refrigerant in the pump cylinder flashing 25 into a gas on the suction stroke of the pump piston, and means for varying the level of the head of brine in said brine tank.

17. Refrigeration system including an evaporator and a condenser with high and low side connections therebetween, an expansion valve in 30 said high side connection adjacent said evaporator, a pump for maintaining a head of liquid refrigerant in said low side up to said expansion valve, said pump bridging the high and low side 35 connections between said evaporator and condenser, having motor and pump cylinders intercalated in said high and low side connections respectively with synchronously moving pistons

therein, the motor piston being actuated by gaseous pressure generated by expansion of the gaseous refrigerant, said condenser including a coil in a brine tank, said coil being placed at such elevation that the level of liquid refrigerant in 5 said condenser is above the upper limit of travel of the pump piston to prevent the liquid refrigerant within said pump cylinder flashing into a gas on the suction stroke of the pump.

18. Refrigeration system including an evaporator and a condenser with high and low side connections therebetween, an expansion valve in said high side connection adjacent said evaporator, a pump for maintaining a head of liquid refrigerant in said low side connection up to said expansion valve, said pump bridging said connections, having a motor cylinder intercalated in the high side connection and a pump cylinder in the low side with synchronously moving pistons therein, said motor piston being actuated by gaseous 20 pressure generated by expansion of the gaseous refrigerant mainly in said evaporator, said condenser including a coil in a brine tank, said coil being placed at such height with respect to said pump cylinder that the level of liquid refrigerant in 25 said condenser is above the upper limit of travel of the pump piston, means for maintaining a head of brine in said brine tank above the level of at least a portion of said pump cylinder, and means for conducting brine from said brine tank 30 about said pump cylinder, the maintenance of a head of liquid refrigerant above the upper limit of said pump piston, and the maintenance of a head of brine above the level of at least a portion of the pump cylinder together preventing the 35 liquid refrigerant in the pump cylinder flashing into a gas on the suction stroke of the pump piston.

MARION R. MOORE.
